(57) **CLAIM**

The ornamental design of an adjustable enclosure covering, as shown and described.

DESCRIPTION

FIG. 1 is an isometric view of the adjustable enclosure covering of the present invention with side flaps down;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is an isometric view thereof with the side flaps up.

The broken lines are for illustrative purposes only and form no part of the claimed design.
